TAPE PRINTING AND PROJECTING APPARATUS

August D. Eitzen, Rockville Centre, N. Y., assignor to News Projection Corporation, New York, N. Y., a corporation of New York

Application March 22, 1930, Serial No. 437,963
Renewed May 4, 1934

12 Claims. (Cl. 88—24)

My invention relates to tape printing and projecting apparatus, of a type sufficiently represented by a tape printer such as a stock ticker combined with a suitable projector for throwing 5 the tape image on a screen.

The principal object of the invention is to provide for projecting a plurality, or specifically, as here shown, two images of the tape on corresponding screens, from a single tape and light source, and more particularly to so direct and move the tape over two adjacent and parallel light apertures that difficulties heretofore experienced in turning and guiding the tape between the apertures are avoided.

15 With parallel light apertures it has heretofore been necessary to pass the tape between the apertures over a substantially V-shaped guide or shoe, or guide rollers in angular relation, the tape being advanced by a single puller located beyond 20 the second aperture (with respect to direction of tape movement) and difficulty has been experienced, such as sticking of the tape on the intermediate guide, improper direction of the tape by rollers, stretching of the tape, etc.

25 The present invention provides, as briefly described, two substantially independent tape pullers, one of which acts on the tape at a point beyond the first aperture to advance the tape from the ticker and over said aperture, and the other 30 puller acts on the tape at a point beyond the second aperture to advance the tape over the last named aperture. Between the apertures the tape is reversed by forming in it a substantially free or unsupported U-loop so that when, for example, 35 the printed face of the tape passing over the first aperture is outward, the printed surface as it passes over the second aperture is downward or inward in relation to the aperture and condensing lens. The first and second tape pullers.

40 are controlled by loops in the tape at proper points in such manner that the reversing bend in the tape between the apertures is kept at proper length and in proper form without definite guiding or support, except at points adjacent the 45 projector housing where the tape is engaged by the feed rolls of one puller. To provide for independent light beams through the apertures and to the respective screens from a single light source, suitable lenses and reflecting means are provided 50 to direct the beam from the lamp to and through the apertures, and objectives and mirrors are arranged to direct portions of the beam from the respective apertures to properly located screens, a mirror being interposed between one 55 of the apertures and the corresponding objec-

tive, to divert that portion of the total beam to the objective and therefrom to the corresponding screen, while the portion of the total light beam passing through the other aperture may go directly to the corresponding objective and so to 5 the directing mirrors and screen.

These and other features, capabilities and advantages of the invention will appear from the subjoined detail description of one embodiment thereof, illustrated in the accompanying drawings, in which

Fig. 1 is a view largely of a diagrammatic character, representing in elevation printing and projecting apparatus embodying the invention in one form;

Fig. 2 is a view in vertical section, from the right of Fig. 1, showing essentials of the projector, mirror, lens and screen arrangement, with other parts omitted; and

Fig. 3 is a top plan, enlarged, showing principally the light apertures, and tape guiding, driving and controlling means.

In Fig. 1, 1 is a tape printer of the stock ticker type and 2 designates the associated projector as a whole. The projector includes a lamp housing 3, Fig. 2, having an extension 4 conveniently called a lens housing and in the top of this housing are parallel light apertures 5 and 6 called for convenience the first and second aperture, each of a length corresponding to a desired length of 30 printed tape.

The ticker may be so arranged, as best shown in Fig. 3, that the tape 7 goes directly (as viewed in plan) in a straight line and without transverse twist or bend to the lens housing 4 so that a portion 8 of the tape passes over the first aperture 5, with its printed face upward. At a point beyond the first aperture and beyond the housing 4 (at the right of Fig. 3) the tape is turned downward and at the same time directly laterally, 40 forming a U-bend 9, and after passing through this bend a portion 10 of the tape passes over the second aperture 6 with the printed face downward. The reversing bend 9, because of the guiding and driving means employed, may be substantially free or unsupported.

To draw the portion 8 of the tape over the first aperture (and at the same time to feed the tape into the reversing bend 9) I provide a first tape pulling mechanism comprising a feed roll 11 and 50 an idler roll 12 carried by a spring actuated lever 13, the idler roll having the tape in contact with the main feed roll. These feed rolls engage the tape just after it leaves the first aperture, or at the right of the lens housing, Figs. 1 and 3. The 55

feed rolls may be driven in any convenient way. As illustrated, a motor 15 for the first pulling mechanism is located adjacent the bottom of the projector and drives through suitable gearing in a case 17 a vertical shaft 18 which is connected to the main feed roll 11 as by bevel gears 19.

The first tape puller is controlled by a bend or loop 20 in the tape between the ticker and the projector. A follower, or puller controlling finger 21 runs on this loop and since it engages the printed face of the tape, this roll desirably has annular end and center flanges 22 and 23 which run on side and central unprinted strips of the tape to avoid any contact of the printed 15 characters with the roll, and similarly other roller or stationary guides engaging the printed face of the tape may have such annular flanges or ribs, as will be understood without further explanation in referring to such subsequent guide 20 devices. The roller or loop follower 21 is carried by an arm 25 pivotally mounted and connected to a switch such as a mercury switch enclosed in a switch box 26 supported from the projector housing 4, and the switch is interposed 25 in the circuit of puller motor 15 so that when the ticker stops the loop 20 is shortened by continued advance of the tape by the puller 17 and when shortened to a predetermined point the switch is actuated to break the motor circuit, 30 and tape advance is discontinued; when the ticker again operates and advances the tape the loop is lengthened at a predetermined point, the switch is moved to close the motor circuit and thereupon the puller again advances the tape 35 over the first aperture and to the reversing bend 9.

The second tape puller 30, as diagrammatically illustrated in Fig. 1, is located in a convenient position, which may be below the projector. This puller advances the tape from the reversing bend 9 to and over and away from the second light aperture 6. At a point beyond the second aperture (at the left in Fig. 3) the tape passes over a suitable guide, such as the roller 45 31, and thence downward to the puller 30 which has tape driving rolls 34 as usual, and also has a take-up reel 32 with yieldable or frictional driving means, as usual, to rewind the tape. The second puller is driven by a motor 33.

50 The second tape puller or its motor 33 is controlled by a second tape follower or finger 35 similar to finger 21, running on a portion of the tape adjacent or forming a part of the reversing bend 9 or at a point close to the tape guide 55 36 located just ahead of the second light aperture. This portion 37 of the tape, in other words, constitutes a second controlling loop to control the second puller through finger 35 which is carried by a pivotally mounted arm 38 arranged to 60 actuate a suitable switch, such as a mercury switch within the switch box 39 supported on the lens housing 4. This switch is in the circuit of the second puller motor 33 so that as the loop at 37 is lengthened or shortened (depending on 65 supply of tape to the reversing bend 9 by the first puller rolls 11 and 12) the second tape puller is operated accordingly to advance the tape over the second aperture, and also to maintain the reversing bend 9 of proper length between the 70 two apertures.

The driving and control circuits for the tape pullers and their switches are sufficiently represented in Fig. 1 in which a lead 45 goes from one side of the power line (as represented by one 75 prong of the attachment plug 46) to a branch-

ing point 47. From the branching point a lead 48 goes to one side of the switch in switch box 26 (that is to one of the terminals of the mercury switch therein) and from the branching point 47 a lead 49 goes to one of the terminals 5 of the mercury switch in box 39. From the second terminal of the switch in box 26, lead 50 goes to one terminal of motor 15 of the first tape puller. From the second terminal of the switch in box 39 a lead 51 goes to one terminal of motor 33 of the second tape puller. A common lead 52 branched at 53 goes to the second terminal of each of the puller motors, completing the puller drive and control circuits. Thus, the switch in box 26 under control of the tape loop 15 20 controls in an obvious way the action of the first tape puller 17, and the switch in box 39 under control of the second tape loop 37 controls the action of the second puller 30.

It is desirable to provide frictional retarding 20 means to properly tension or retard the tape as it passes over each of the apertures. Such retarders are the friction members 54 pivotally mounted at 55 and having adjustable weights 56, the friction members being arranged to bear on 25 the tape and retard it in cooperation with the guides, at points just ahead of each aperture thus reducing or eliminating jerking of the tape, etc., caused by puller actions.

A desirable arrangement of the projector 30 proper, that is, light source, lenses, mirrors and screens, to cooperate with plural light apertures and tape driving and directing means of the character above described, is best shown in Fig. 2. The lamp 60 in housing 3 is arranged to 35 throw a beam through suitable condensers, such as 61 and 62, in a horizontal direction to a mirror 63 in lens housing 4, the mirror being at an angle of 45° to the axis of the beam through the primary condensers. A reflector 64 may be 40 placed behind the lamp, as usual.

The beam reflected by mirror 63 passes through a condensing lens 65 secured below the top wall of the housing 4 and portions of the beam issuing from condenser 65 pass through the respective apertures. Suitable objective lenses in a casing 67 are arranged to receive directly the beam issuing from the first aperture 5. A mirror 68 is placed at an angle of 45°, in a position to intercept the beam from the second aperture 6 50 and direct it through objective lenses in a case 69, the axis of this objective being horizontal. Mirrors 70 and 71 are arranged above the objective 67 in proper angular positions to direct therefrom to the screen 72. Mirrors 73 and 74 55 are arranged operatively between objective 69 and a second screen 75 to direct the second beam properly to that screen. The described number and arrangement of mirrors for each of the light beams is appropriate to the position or location 60 of the printed tape as it passes over each aperture. That is, with respect to the first aperture 5, the tape has the printed characters upward so that they read right side up, as viewed in plan, Fig. 3. This image is reversed once by the objective 67 and again by mirror 70 to read right side up as reflected by mirror 71 upon screen 72, when that screen is viewed from the left of Fig. 2. On the tape strip 10 passing over the second aperture 6 the characters are on the under side of the tape or in reversed position, as viewed in plan through the transparent tape. The characters are reversed once by mirror 68, again by objective 69, again by mirror 73 and are then thrown by mirror 74 in proper position on 75

screen 75, as viewed from the right thereof, Fig. 2.

The lens, mirror and screen arrangement as described provides for the least possible number 5 of mirrors and therefore the greatest conservation of light, in connection with parallel light apertures and the tape moved over the apertures in the manner stated; thus, for the beam passing through the first aperture and objective 67 only 10 two mirrors are required, as at 70, 71, and for the other light beam only three are required, namely 68, 73 and 74.

In addition to other advantages mentioned the 15 double puller arrangement as described, reduces to a minimum stretching of the tape, since the total stretch in any portion of tape is limited practically to the short portion passing over each of the apertures or at most the portion between a friction device, such as 54, and the pulling elements 20 located near the opposite end of the corresponding aperture. This is in distinction from other arrangements where a single tape passes a plurality of apertures with a single tape puller, and the stretch in such cases is equal to the total 25 stretch in the entire length of tape passing over all the apertures.

It is obvious that various changes and modifications may be made in the details of construction without departing from the general spirit of 30 the invention set forth in the appended claims.

I claim:—

1. Projecting apparatus of the character described comprising a housing having adjacent parallel light apertures, a common source of 35 light for throwing light through the apertures, means for printing a continuous tape, and for guiding and directing said continuous printed tape over the apertures with a substantially free reversing bend in a portion of the tape between the apertures, in combination with a tape printer, a tape puller arranged to draw the tape from the printer over the first aperture and to the reversing bend according to the slack formed anterior to the first aperture, and another tape puller arranged to draw the tape from the reversing bend and over the second aperture according to the slack formed in the reversing bend, and means co-operating with said drawing means to maintain a substantially constant supply of tape 50 in said bend as the latter varies in length owing to the variable action of said transmitter.

2. Projecting apparatus of the character described comprising a housing having adjacent parallel light apertures, means for throwing light 55 through the apertures, means for guiding and directing a continuous printed tape over the apertures with a substantially free reversing bend in a portion of the tape between the apertures, in combination with a tape printer, a tape puller arranged to draw the tape from the printer over the first aperture and to the reversing bend, another tape puller arranged to draw the tape from the reversing bend and over the second aperture, controlling means for the first tape puller actuated by a portion of the tape between the printer and the first aperture according to the slack 60 formed therein, and controlling means for the second tape puller actuated by a portion of the tape between the apertures according to the slack formed in the reversing bend.

3. Projecting apparatus of the character described comprising a housing having adjacent parallel light apertures, means for throwing light 65 through the apertures, means for guiding and directing a continuous printed tape over the

apertures with a substantially free reversing bend in a portion of the tape between the apertures, in combination with a tape printer, a tape puller arranged to draw the tape from the printer over the first aperture and to the reversing bend, another tape puller arranged to draw the tape from the reversing bend and over the second aperture, controlling means for the first tape puller actuated by a portion of the tape between the printer and the first aperture, according to the slack 10 formed therein, and controlling means for the second tape puller actuated by a part of the tape included in said reversing bend according to the slack formed therein.

4. Projecting apparatus of the character described 15 comprising a housing having closely adjacent parallel light apertures, a common source of light for throwing light through the apertures, means for guiding and directing a continuous printed tape over the apertures with a substantially free reversing bend in a portion of the tape 20 between the apertures, an objective lens group for each aperture, one arranged to receive a light beam directly from its aperture, and a mirror angularly arranged between the second aperture 25 and its objective to intercept the beam from the aperture and divert it to the other objective.

5. Projecting apparatus of the character described comprising a housing having adjacent parallel light apertures, a common source of 30 light for throwing light through the apertures, means for guiding and directing a continuous printed tape over the apertures with a substantially free reversing bend in a portion of the tape 35 between the apertures, an objective lens group for each aperture, one arranged to receive a light beam directly from its aperture, a mirror angularly arranged between the second aperture and its objective to intercept the beam from the aperture and divert it to the other objective, a 40 screen and mirrors arranged to direct the beam from the first objective to the screen, another screen, and mirrors arranged to direct the beam from the second objective to said screen.

6. In printing and projecting apparatus, the 45 combination of a tape printer, a projector comprising a casing and adjacent parallel light apertures therein, a common source of light for said light apertures, tape guiding means, a first tape puller arranged to pull the tape from the ticker 50 over the first aperture according to the slack formed in the tape anterior to the first aperture, and a second tape puller arranged to pull the tape over the second aperture according to the slack formed in the tape between the two apertures.

7. In printing and projecting apparatus, the 60 combination of a tape printer, a projector comprising a casing and adjacent parallel light apertures therein, a common source of light for said light apertures and tape supporting and guiding means arranged to form in the continuous tape between the apertures a substantially free reversing bend, said supporting and guiding means including a tape drawing device in engagement with the tape at the end of the first aperture and a tape controlling device in engagement with the tape at the entrance to the second aperture.

8. In printing and projecting apparatus, the 70 combination of a tape printer, a projector comprising a casing and adjacent parallel light apertures therein, a common source of light for said light apertures, tape guiding means, a first tape puller arranged to pull the tape from the ticker 75

- over the first aperture, a second tape puller arranged to pull the tape over the second aperture, a follower running on the tape anterior to the first aperture, and means controlled by the follower and controlling the first tape puller, a second follower running on the tape anterior to the second aperture, and means controlled by the second follower and controlling the second tape puller.
9. In printing and projecting apparatus, the combination of a tape printer, a projector comprising a casing and adjacent parallel light apertures therein, a common source of light for said light apertures, tape guiding means, a first tape puller arranged to pull the tape from the ticker over the first aperture, a second tape puller arranged to pull the tape over the second aperture, a follower running on the tape anterior to the first aperture, and means controlled by the follower and controlling the first tape puller, a second follower running on the tape anterior to the second aperture, and means controlled by the second follower and controlling the second tape puller, each tape puller including a motor, and each controlling mechanism including a switch controlled by the follower and acting on the corresponding motor circuit.
10. Projecting apparatus of the character described comprising a housing having closely adjacent parallel light apertures, a common source of light for throwing light through the apertures, means for successively guiding and directing a continuous printed tape over the apertures with the printed matter of the successive tape portions facing in opposite directions, an objective lens group for each aperture, one arranged to receive a light beam directly from its aperture, and a mirror angularly arranged between the second aperture and its objective to intercept the beam from the aperture and divert it to its objective.

11. Projecting apparatus of the character described comprising a housing having adjacent parallel light apertures, a common source of light for throwing light through the apertures, means for successively guiding and directing a continuous printed tape over the apertures with the printed matter of the successive tape portions facing in opposite directions, an objective lens group for each aperture, one arranged to receive a light beam directly from its aperture, a mirror angularly arranged between the second aperture and its objective to intercept the beam from the aperture and divert it to the other objective, a screen and mirrors arranged to direct the beam from the first objective to the screen, another screen, and mirrors arranged to direct the beam from the second objective to said screen.

12. Projecting apparatus of the character described comprising a housing having adjacent parallel light apertures, a common source of light, means for successively guiding and directing portions of a successive continuous printed tape over the apertures with the printed matter of the successive tape portions facing in opposite directions, means for directing a converging light beam from said common source of light at said adjacent light apertures to form two subordinate light beams after emerging from the two tapes, an independent screen for the images produced by the portion of tape at each light aperture, reflecting means arranged to direct a subordinate beam emerging from one portion of the tape to one of said screens, and another reflecting means arranged to direct the subordinate beam emerging from the other portion of the tape to the other of said screens.

AUGUST D. EITZEN. 40
